**WATER CRAFT FOR THE TRANSPORT OF
WHEELED VEHICLES**

Richard Creighton King, Angmering, England

Application October 16, 1956, Serial No. 616,196

Claims priority, application Great Britain
November 4, 1955

5 Claims. (Cl. 114—60)

This invention relates to a floating decked craft, hereafter referred to as a pontoon, for rendering water-borne a wheeled caravan or trailer, hereafter referred to as a caravan, of the kind which is normally towed on land behind a motor vehicle.

One of the objects of the present invention is to provide a small pontoon onto which a caravan may be embarked by wheeling the same directly from the land onto the deck of the pontoon and which is so constructed that the embarked caravan can be accommodated in such manner that it will not become displaced by the normal motions of the craft when cruising.

Broadly the present invention consists in means for rendering water-borne a wheeled caravan comprising a decked craft or pontoon having a construction such that the caravan may be embarked by wheeling the same from the land onto the deck of the craft and when thus embarked to have its wheels partially accommodated below deck level and the underside of the body of the caravan supported by or in close proximity to the upper surface of said deck.

The invention also comprises a decked craft or pontoon for rendering water-borne a wheeled caravan in which the continuity of the deck is broken by one or more openings adapted to receive the wheels of the caravan and permit the same to be partially accommodated below the level of the deck and the underside of the body of the caravan to be supported by or in close proximity to the upper surface of said deck.

The invention still further comprises a decked craft or pontoon, for rendering water-borne a wheeled caravan, which has one or more openings in its deck to permit the entrance therethrough of the wheels of the caravan, a well beneath each opening to accommodate each said wheel and means within each well for supporting the caravan by its wheels, for lowering the caravan to a position where its wheels are partially accommodated within the one or more wells and the underside of its body is supported by or in close proximity to the upper surface of the said deck and for elevating the caravan to bring the wheels to deck level so that the caravan may be disembarked.

Where the caravan to be embarked has a single pair of travelling wheels these may be accommodated in the craft by forming its deck with a single transverse opening amidship of sufficient width to permit the entrance therethrough of the wheels of the caravan and beneath said opening a single well formed by a pair of spaced transverse water-tight bulkheads said well being sufficiently deep as partially to accommodate the said wheels with the underside of the body of the caravan supported by or in close proximity to the upper surface of the deck of the craft.

In practice the wheels of the caravan may enter and leave the one or more wells by fitting a lifting jack in each well adapted to lower and raise the caravan vertically into and out of the lowered position.

These jacks may be independently operated or they

2

may be interconnected. For example where four jacks are provided they may either be individually operable or they may be interconnected so as to be operable either in pairs or simultaneously.

5 In order that the invention may be clearly understood and carried into effect an embodiment of the same will now be described, by way of example, by aid of the accompanying drawings in which:

Fig. 1 is a view in perspective of a pontoon having 10 a single transverse well amidship to receive the wheels of a two wheeled caravan, an outline of which is shown in chain dotted lines in the figure.

Fig. 2 is a top plan view of the craft shown in Fig. 1. Fig. 3 is a side view of the same partly sectioned to 15 show the bulkheads used in the construction.

Fig. 4 is a transverse section on the line 4—4 in Fig. 2.

Fig. 5 is a transverse section on the line 5—5 in Fig. 2.

Fig. 6 is an end view, partly in section, showing one 20 of the four screw jacks used in the pontoon shown in Fig. 1.

Fig. 7 is a view taken at right angles to Fig. 6 and looking towards the front of the components therein shown.

The pontoon illustrated in the drawings comprises a 25 straight sided hull 1, having a flat bottom 2, terminating at each end in upwardly inclining surfaces or swimheads 3. The hull 1 is covered in by a flat deck 4 and on each side thereof are longitudinally extending catwalks 5 which are supported from the hull by brackets 30 6 with the upper faces or treads of the catwalks flush or level with the upper surface of the flat deck 4.

The interior of the hull 1 beneath the deck 4 is divided 35 into sections by lateral spaced bulkheads, those indicated by the reference numeral 7 having apertures 8 in them, see Fig. 5, permitting communication between adjoining sections and the remainder, indicated by the reference numeral 9, being solid to render adjoining sections watertight.

The water-tight bulkheads 9 are arranged so that a 40 pair thereof provide the transverse sides of a well 10 which extends the full width of the hull 1 and is open at the top by a correspondingly shaped break in the continuity of the flat deck 4.

The well 10 is dimensioned so as to be capable of 45 accommodating the lower portions of the wheels 11 of a caravan 12, which is lowered by a jacking system, hereafter to be described until the wheels are partially accommodated in the well 10 and the undersurface of the caravan is supported directly or indirectly by the upper 50 face of the deck 4.

Where the underside of the caravan is plane and not 55 broken by protuberances it will be safe to allow the caravan to be directly supported by the deck 4 when the caravan is in its lowered position but if protuberances are present it is advisable to allow the caravan to be supported by wooden dunnage or blockings so placed as to distribute the load and prevent the valence or underside of the caravan from coming into contact with the deck 4.

60 The upper surface of the craft comprising the deck 4 and the catwalks is circumscribed by bulwarks 13. These include guard rails 14 along the sides of the catwalks 5 merging into fixed and solid corner pieces forming a part of the bulwarks. The transverse portions of the 65 bulwarks comprise removable or hinged sections 15 which are removed or lowered to form an entrance or an exit for the caravan when embarking or disembarking the same.

65 In the embodiment illustrated the caravan, when 70 embarked, is handled by a mechanical jacking system and this system comprises four rotatable screwed rods 16,

mounted vertical, one in each corner of the well 10, on a gimbal type footstep bearing 17, see Figs. 6 and 7. In threaded engagement with each rod 16 is a nut 18 which nuts are fashioned to provide a four point support for a rectangular frame 19. This frame 19 in turn acts as a support for a pair of longitudinal channel guides 20 which are spaced apart a distance equal to the track of the caravan's wheels.

The screwed rods 16 are rotated by levers, not shown, engageable with the squared upper ends 21 of the rods and this causes the nuts 18, which are held against rotation by their engagement with the frame 19, to traverse up or down the rods.

In embarking a caravan the jacks are operated to raise the frame 19 and the channel guides 20 to deck level. The caravan wheels are then run onto the channel guides and are lowered thereon into the well 10 by suitably rotating the rods 16 of the jacking system.

To disembark the caravan the jacking system is operated to raise the channel guides with the supported caravan wheels from the well 10 up to deck level when the caravan is free to be wheeled across the deck 4 of the craft, down suitable runways, not shown, and onto land.

In the simple form of jacking system shown the rods 16 are intended to be operated by hand by persons standing on the catwalks 5 on opposite sides of the well.

Although the craft shown in the drawings is provided with catwalks 5 the same are only required where the width of the deck is substantially the same as the width of the caravan to be accommodated. If, therefore, the craft is large enough to accommodate a caravan on its deck and still leave sufficient room for persons to walk around it in safety, the aforesaid laterally extending catwalks will not be required.

If the craft with caravan aboard is intended to be used for cruising the same can conveniently be arranged to receive an outboard type of motor and propeller and in the design of hull illustrated provision for the reception of such an engine is made by including an aperture 22 in one of the transverse portions 15 of the bulwarks to accommodate the rudder and engine controls.

The hull of the pontoon is designed so that its components may be prefabricated and assembled in a place close to the launching site so as to avoid having to use specialized forms of road transport.

For the above purpose the hull proper is built up from suitably scarfed and drilled planking and in the case of the flat bottom of the hull the planks are assembled with caulking material between their opposing longitudinal edges and the whole are clamped tightly together by transverse metal tie rods 23 which are nutted at one or both ends for this purpose. These tie rods also act to bolt the flat bottom 2 of the hull to the sides thereof.

If desired the pontoon may be used as a floating camping site for a caravan, and for cruising purposes it may either be self-propelled or it may be towed by a motor boat or other suitable craft.

To enable a gangplank to be used when the pontoon is moored a hinged door 24 guarding an opening in the forward bulwark is provided. The usual fairleads 25 are also provided at one or both ends of the pontoon.

What is claimed is:

1. A water craft for transporting wheeled vehicles

comprising, in combination a flat bottom hull; a deck on top of said hull, said deck having at least one opening extending transversely thereof intermediate its ends and forming, with said hull, a well in said deck; water tight bulkheads extending across said hull at each edge of the opening between said bottom and said deck; a pair of transversely spaced wheel guides in said well extending longitudinally of the craft; and means in said well for adjusting said guides between an elevated position flush with said deck to receive the wheels of a vehicle and a lowered position wherein the wheels are in said well with the vehicle body supported from said deck.

2. A water craft as claimed in claim 1 including a catwalk supported outboard of each side of the hull substantially flush with said deck.

3. A water craft as claimed in claim 1 in which said guides comprise a pair of channels supported on members extending across the well and said adjusting means engages said cross members.

4. A water craft as claimed in claim 3 in which said adjusting means comprises pairs of jacks each engaged with a cross member.

5. A stable water craft for transporting wheeled vehicles secured against movement therein comprising, in combination a hull having a flat bottom; a deck closing the top of said hull, said deck having at least one opening extending transversely across the top thereof between the ends of said deck; said opening in said deck and said hull cooperating to form a well in the craft extending below the waterline; at least a pair of transversely directed spaced wheel-carrying guides positioned in said well and extending longitudinally of the craft, and means mounted on said hull in said well for carrying said guides and adjusting the height thereof between a lowermost

30 position in which said guides extend substantially flush with said flat bottom and an uppermost position in which said guides extend substantially flush with said deck, whereby with the wheels of a wheeled vehicle supported in said guides the latter are lowered to lower the wheels into said well until the vehicle is carried from said deck and said wheels are seated in said well to secure the vehicle from shifting movement in the craft and whereby once the craft is loaded the combined center of gravity of the craft and vehicle is lowered in the direction of the center of gravity of the water displaced by the craft to thereby improve the stability of the craft.
